CLAIM

The ornamental design for a medical adhesive applicator, as shown and described.

DESCRIPTION

FIG. 1 is a right side elevational view of a medical adhesive applicator, showing the new design;

FIG. 2 is a rear elevational view thereof;

FIG. 3 is a left side elevational view thereof;

FIG. 4 is a front elevational view thereof;

FIG. 5 is a top plan view thereof;

FIG. 6 is a bottom plan view thereof;

FIG. 7 is a perspective view thereof; and,

FIG. 8 is a perspective view thereof.

The broken lines shown in FIGS. 1-8 illustrate portions of the medical adhesive applicator that form no part of the claimed design.
